RATCHET FOOTAGE INDICATOR FOR
MOTION PICTURE APPARATUSCarter J. Hughey, Rochester, N. Y., assignor to
Eastman Kodak Company, Rochester, N. Y., a
corporation of New JerseyApplication September 23, 1937, Serial No. 165,375
In Germany September 25, 1936

8 Claims. (Cl. 74—125)

The present invention relates to a ratchet assembly and more particularly to a ratchet type of footage indicator for motion picture apparatus.

5 Footage indicators of the ratchet type as used in the motion picture art are generally mounted upon the casing for the apparatus, while the actuating means for such footage indicator is mounted on the internal mechanism of the apparatus. Unless the actuating means is assembled in a very definite and accurate relation with respect to the footage indicator, the operation of the footage indicator by the actuating means may be extremely critical and subject to failure 10 if the actuating means is not precisely mounted within the apparatus casing and with respect to the footage indicator.

The primary object of the present invention is the provision of a ratchet assembly comprising 20 in combination an actuating means, a driven means, and an intermediate motion transmitting means which will operate to advance the driven means irrespective of any variations in positioning of the actuating means or in the 25 actuating movement thereof.

Another object of the invention is the provision in a ratchet assembly of an intermediate motion transmitting means including a normally arcuate resilient portion, which arcuate portion is straightened by the action of the actuating means for advancement of the driven 30 means.

A further object of the invention is the provision of an intermediate motion transmitting 35 means for a ratchet type of footage indicator including a pivotally mounted arm carrying an arcuate spring portion which is intermittently straightened and permitted to return to arcuate position for intermittent advancement of a driven means having a plurality of teeth.

Still another object of the invention is the provision of an intermediate motion transmitting means for a ratchet type of footage indicator and which means comprises a single spring member 45 having one end engaging the teeth of the footage indicator disc to prevent reverse movement thereof and having an arcuate portion at its other end for engaging a tooth of the indicator disc and which arcuate portion is intermittently straightened for intermittent advancement 50 of the teeth on said disc.

Other and further objects of the invention will be suggested to those skilled in the art by the following description.

55 The above and other objects of the invention

are embodied in a ratchet assembly including the combination with an actuating means including an engaging portion, and a driven means having a plurality of teeth, of an intermediate motion transmitting means including a normally arcuate resilient portion located to engage the teeth of said driven means, arranged to be intermittently moved by the action of the engaging portion of said actuating means into a straightened position for advancement of a tooth of said driven means and then permitted normally to return to arcuate form for engagement with an adjacent tooth on said driven means.

Reference is hereby made to the accompanying drawing wherein similar reference characters designate similar elements and wherein:

Fig. 1 is a side elevation of a motion picture apparatus equipped with a ratchet type of footage indicator according to the invention, the casing of said apparatus being broken away for better illustration of the details of the ratchet construction.

Fig. 2 is an enlarged detail of the ratchet assembly of Fig. 1 illustrating conditions just prior to operation of the intermediate motion transmitting means.

Fig. 3 is a similar detail to enlarged scale but showing the intermediate motion transmitting means with the arcuate resilient portion thereof in extended or straightened position.

Fig. 4 is a side elevation of a modified form of the ratchet type of footage indicator according to the invention.

Although the improved intermediate motion transmitting means for a ratchet assembly, according to the invention, is illustrated and described with respect to a motion picture apparatus, it is to be understood that the invention is also applicable to all types of ratchet assemblies.

According to the illustrated embodiment of the invention, the ratchet assembly is provided within a motion picture apparatus housed in a casing having side walls 10 and an edge wall 11. The actuating means for said ratchet assembly may be mounted within said casing and includes an eccentrically located engaging portion. Such an actuating means may comprise a driving member, such as a spring motor drum 12 which is rotatable about a shaft 13 extending between the side walls 10 of the casing. Spring motor drum 12 contains a spring 12' which has one end attached to the drum 12 and the other end, not shown, connected to the shaft 13. A pin 14 is eccentrically mounted on drum 12 to provide the aforementioned eccentric engaging portion.

The driven means is movably mounted within said casing and may comprise an indicator disc 15 which may be pivotally mounted on side walls 10 by a pin 20. Teeth 16 of a definite and substantially uniform pitch extend around the periphery of disc 15. A series of footage numerals 17 may be engraved on indicator disc 15 and may be visible from the exterior of the apparatus through the window 18 provided in said side 10 wall 10.

According to the preferred form of the invention, a resetting knob 19 on the exterior of side wall 10 may be connected to pin 20 for resetting of the footage indicator. Also a holding pawl 15 to prevent retrograde movement is preferably supplied although it should be understood that the same result may be accomplished by sufficient frictional resistance in the mounting for the driven means or in the pivotal support for disc 15. Such a holding pawl, see Fig. 1, may comprise a wire spring 21 mounted on the interior of side wall 10 by a screw 22, having one end engaging the teeth 16 of disc 15 to prevent reverse rotation thereof and having the other end encircling a pin 23 also on the interior of side wall 10.

The intermediate motion transmitting means intermittently transmits the movement of the actuating means to the driven means. The outstanding feature of the present invention is the provision of a resilient member in such intermediate motion transmitting means and which resilient member is preferably provided as an arcuate resilient portion to be extended or straightened by the action of the engaging portion on the actuating means to advance, tooth by tooth, the driven means.

According to the preferred form of the invention, the intermediate motion transmitting means 40 may comprise an arm 24 which is pivotally mounted by a pin 25 upon the interior of side wall 10 and which includes an arcuate spring portion 26 having one end connected to or integral with arm 24 and having a free end 26' engaging the peripheral teeth 16 of disc 15. Arm 24 may also be provided with a curved edge 24' which is engaged by the pin 14 on spring drum 12 so that upon rotation of drum 12 in the direction of the arrows, see Figs. 2 and 3, arm 50 24 is rotated in a clockwise direction, see Fig. 3.

Said arcuate spring portion 26 normally assumes a curved position as shown in Fig. 2 and in which normal position the distance between the free end 26' and the point of attachment to the arm 24, or the chord subtending the arc of spring portion 26, is indicated by the dimension *a*. As the pin 14 moves in a clockwise direction, the camming action between said pin 14 and the curved edge 24' of arm 24 results in rotation of said arm 24 and in a straightening or extension of said arcuate spring portion 26. This condition is illustrated in Fig. 3. It should also be noted that during the straightening or extended position of arcuate portion 26, the distance between the free end 26' and point of attachment to arm 24 is represented by the dimension *b* which equals approximately the length of the arc of spring portion 26. Such extension of portion 26 is sufficient to advance a tooth 16 on the disc 15 a distance greater than or exceeding the pitch of said teeth 16. In other words, the dimension *b* is greater than the dimension *a* plus the pitch of the teeth 16 or the difference between the length of the arc of arcuate spring portion 26 and the chord subtending that arc is

greater than the pitch but less than twice the pitch of a tooth on disc 15. As a result, disc 15 will be rotated angularly a distance of one tooth.

After pin 14 passes out of engagement with arm 24, the resiliency of arcuate spring portion 26 will return it to its normal position and so that the free end 26' thereof comes into engagement with the adjacent or succeeding tooth 16 on disc 15.

According to another form of the invention, 10 the holding pawl and arcuate spring portion of the intermediate motion transmitting means are simultaneously provided. A single spring member, such as a spring wire 27, is mounted on the interior of side wall 10 by studs 28 and 29. Said 15 spring wire 27 has one end 30 in continuous engagement with the teeth 16 of disc 15 to prevent retrograde or reverse movement thereof. The intermediate portion 31 is curved around said stud 28 and bears against stud 29 for mounting 20 of spring wire 27 on the interior of side wall 10. An arcuate spring portion 32 is formed from the other end of spring wire 27 and has a free end 32' abutting against one of the teeth 16 on disc 15.

As before, upon rotation of spring drum 12 in the direction of the arrow, see Fig. 4, the pin 14 strikes against the arcuate spring portion 32 to extend or straighten the same and to move one of the teeth 16 a distance slightly exceeding the pitch of such tooth. After pin 14 moves beyond arcuate spring portion 32, said spring portion returns to its normal position and is curved sufficiently to come into engagement with the adjacent or succeeding tooth 16 on disc 15. During this return of arcuate spring portion 32 to its normal condition, the other end 30 of spring 30 27 acts to prevent any reverse rotation of disc 15 by reason of such return of the arcuate spring portion 32. 40

From the foregoing disclosure of the invention it will be understood that the advancement of the driven means a distance exceeding the pitch of a tooth is determined primarily by the curvature of arcuate spring portions 26 and 32. 45 As a result, variations in the eccentricities of pin 14 on spring drum 12 or variations in the mounting of spring drum 12 with respect to arm 24 or spring wire 27 to increase or decrease the deflection of arcuate spring portions 26 or 32 will not 50 cause a corresponding variation in the advancement of a tooth 16. In other words, the straightening or extension of arcuate portions 26 or 32 will occur sufficiently to advance a tooth 16 of the driven means upon angular movements of 55 arm 24 or small deflections of arcuate spring portion 32 and greater angular movements of arm 24 or deflections of spring portion 32 will not alter the advancing action of such arcuate spring portions correspondingly but, as long as 60 there is enough angular movement of arm 24 or deflection of spring portion 32 to advance a tooth 16, any additional movements by reason of inaccuracies of manufacture or assembly do not affect the operation of the intermediate motion transmitting means to result in inoperativeness of the ratchet assembly. 65

Since many variations of the invention are possible, the scope of the invention is not to be limited in any respect by the present disclosure 70 but is defined in the appended claims.

Having now particularly described my invention what I desire to secure by Letters Patent of the United States and what I claim is:

1. In a ratchet assembly, the combination with 75

- a driven member movably mounted and having a plurality of teeth of a predetermined pitch, of a motion transmitting means for advancing said driven member tooth by tooth and including an arcuate resilient member having a curvature such that the difference between the length of the arc of said resilient member and the length of the chord subtending that arc is greater than the pitch of one tooth but less than twice the pitch of a tooth on said driven member.
2. In a ratchet assembly, the combination with a driven member movably mounted and having a plurality of teeth of a predetermined pitch, of a motion transmitting means for advancing said driven member tooth by tooth and including an arcuate resilient member having a curvature such that the difference between the length of the arc of said resilient member and the length of the chord subtending that arc is greater than the pitch of one tooth but less than twice the pitch of a tooth on said driven member, and a movable actuating means for intermittently moving said motion transmitting means to cause movement of said arcuate resilient member from its arcuate condition to an approximately chordal position.
3. In a ratchet assembly, the combination with an actuating means movably mounted and including an engaging portion, and a driven means also movably mounted and having a plurality of teeth of a predetermined pitch, of an intermediate motion transmitting means including a normally arcuate resilient portion having a free end for engaging the teeth of said driven means, arranged to be intermittently straightened by the action of the engaging portion of said actuating means, adapted upon such straightening to advance a tooth of said driven means a distance greater than the pitch but less than twice the pitch of said tooth, and then returning to normal position for engagement with an adjacent tooth of said driven means.
4. In a ratchet assembly, the combination with a driving member rotatably mounted and including an engaging portion which is eccentrically located, and a driven member rotatably mounted and having a plurality of teeth of a predetermined pitch, of an intermediate motion transmitting means including a normally arcuate resilient portion located to engage the teeth of said driven means, arranged to be intermittently straightened by the action of the eccentric engaging portion of said driving member, adapted by such straightening to be extended for advancing a tooth of said driven member a distance exceeding the pitch but less than twice the pitch of said tooth, and then after disengagement from said engaging portion returning to normal position for engagement with the succeeding tooth on said driven member.
5. In a ratchet assembly, the combination with a driving member rotatably mounted and including an engaging portion which is eccentrically located, and a driven member rotatably mounted and having a plurality of teeth of a predetermined pitch, of a single spring member having one end engaging the teeth on said driven member to prevent reverse rotation thereof, and having an arcuate portion at the other end for engaging a tooth of said driven member and which arcuate portion is intermittently engaged and straightened by said engaging portion to advance said tooth a distance exceeding the pitch thereof.
6. In a ratchet type footage indicator for motion picture apparatus, the combination with a driving member rotatably mounted and including an eccentrically located engaging portion, and an indicating member rotatably mounted and having a plurality of teeth of a predetermined pitch, of an intermediate motion transmitting member including an arm pivotally mounted and located intermittently to be rotated by the engaging portion of said driving member and including an arcuate spring portion for engaging the teeth of said indicating member, intermittently straightened by the intermittent rotation of said arm, and adapted upon said straightening to be extended a distance exceeding the pitch but less than twice the pitch of said tooth for corresponding advancement of said indicating member.
7. In a ratchet type of footage indicator for motion picture apparatus, the combination with a casing, a spring drum rotatably mounted within said casing and carrying a pin eccentrically located, an indicator disk rotatably mounted on said casing and having a plurality of teeth, and a holding pawl on said casing for engaging said teeth to prevent retrograde movement of said disk, of an intermediate member rotatably mounted on said casing, having a portion adapted intermittently to be actuated by said pin for periodic rotation of said member, and including an arcuate spring portion engaging a tooth on said disk, which arcuate portion is straightened by the rotation of said intermediate member to advance said disk a distance greater than the pitch but less than twice the pitch of said tooth; and which arcuate portion normally returns said intermediate member to an initial position with said arcuate spring arm in engagement with the succeeding tooth on said disk.
8. In a ratchet type of footage indicator for motion picture apparatus, the combination with a casing, a spring drum rotatably mounted within said casing and carrying a pin eccentrically located, and an indicator disk rotatably mounted on said casing and having a plurality of teeth, of a single spring member intermediately mounted on said casing, having one end engaging the teeth on said indicator disk to prevent reverse rotation thereof, and having an arcuate portion at the other end for engaging a tooth of said disk, which arcuate portion is intermittently engaged and straightened by said pin to advance said disk and which subsequently and normally returns to arcuate form and into engagement with the succeeding tooth on said disk.

CARTER J. HUGHEY. 65
